UNITED STATES PATENT OFFICE.

JOHN Q. SHERMAN, OF DAYTON, OHIO.

ROTARY PUNCH.

1,423,690.

Specification of Letters Patent. Patented July 25, 1922.

Application filed January 5, 1920. Serial No. 349,372.

To all whom it may concern:

Be it known that I, JOHN Q. SHERMAN, a citizen of the United States, and a resident of the city of Dayton, county of Montgomery, and State of Ohio, have invented 5 certain new and useful Improvements in Rotary Punches, of which the following is a full, clear, and exact description, reference being had to the accompanying drawings, 10 forming a part of this specification.

My invention relates to rotary punch mechanisms, suitable for punching a series of holes in any desired material, and more particularly for punching out a series of 15 holes in strips of paper. It is also employed as an attachment in connection with rotary presses for printing up into forms a continuous web or strip of paper, such as are used in autographic register or multi-graph work.

It will be understood that the mechanism shown apart from the punch itself and the operative parts thereof is selected for purposes of illustration. It should be noted 25 further as to the general type of mechanism that the punches while rotary do not operate like a revolving head to punch out successive crosswise rows of holes from a strip of paper or whatever medium is selected, 30 but punch out the desired series of holes lengthwise as well as crosswise of the strip. I have found that this principle will result in a more certain uniformity of spacing of the holes, and permit of a more accurate 35 and positive operation than revolving head rotary punches which operate to punch but one crosswise set of holes at each step by step movement of the paper, or in other words have a truly continuous mode of 40 operation.

My advantages in structure and operation, and the objects above noted I accomplish by that certain construction and arrangement of parts to be more specifically 45 pointed out and claimed.

In the drawings,

Figure 1 is a side elevation of the complete mechanism.

Figure 2 is a section taken on the line 50 2—2, of Figure 1.

Figure 3 is a side elevation of the punch bars on a larger scale than Figure 1.

Figure 4 is a detail vertical section 55 through the punch bar.

The machine shown has a frame 1, and a power driven gear 2. A storage roll 3 for

paper 4 is shown, said paper being fed by means of a driven roll 5 and contacting with a friction roll 6.

For removal of the paper from the machine no mechanism is shown but it will be understood in the matter that follows that the paper is controlled by the driven roll 5 so that the proper amount goes to the punches. Some sort of control for the paper such as this will be required except where the punches are used in a printing press, or some other material than paper is employed.

The punch bars are driven from the gear 2 by means of a pinion 7. This pinion meshes with a gear 8, which in turn meshes with a pinion 9 on the shaft 10 of the feeding roll 5. The amount of paper issued to the punches is thus controlled absolutely by 75 the relative sizes of the gears and roll 5, the friction roll 6 being adapted to normally press tightly against the said feed roll 5.

Mounted at the receiving end of the punch bar mechanism at each side thereof, are the upper and lower stub shafts 11 and 12, suitably held in the frame and at the issuing end of the punch mechanism are the upper and lower shafts 13 and 14. These shafts 85 support for the upper shafts the cranks 15, 15 and for the lower shafts the cranks 16, 16 these cranks being mounted on the shafts on the inside of the frame 1. Each pair of cranks 15, 16 support cross rods 17 90 and 18, of which 17 are the upper rods at the front and back of the mechanism and 18 are the lower rods. Journaled on the said rods are the desired number of punch bars, of which the male bars are indicated at 19 95 and the female at 20. The bars are held in place by collars 21, secured in position by set screws 22. The desired number of bars can be mounted crosswise of the mechanism and permanently and accurately located by 100 means of the collars 21.

Although but one set of punch bars is shown, it will be understood that normally a device of this character will employ several sets and between the bars of a set are 105 located standards 23 which carry at their upper ends paper supporting plates 24.

On the outside of the frame the pair of stub shafts 11 have rigidly secured to them cranks 25, 25 and the shafts 12 have rigidly 110 secured cranks 26, 26. The shaft 12 at the one side of the machine has mounted fast

thereon a pinion 7 which, it will be remembered, is driven by the gear 2.

Crank 25 and 26 have links 27 and 28 respectively, which at each side of the machine are connected to cylinders 29 and 30. The cylinders 29 and 30 slide in bosses 31, 32 mounted on the frame of the machine.

By this mechanism the shafts 11 and 12 are driven. The gear 2 and pinion 7 impart motion to the shaft 12 and its outer crank 26. Through the medium of the link 28 for its crank 26 and the cylinder 29 and link 27, motion is communicated to the shaft 11. On the interior of the machine the crossbar 17 for the two shafts 11 and the cross-rod 18 for the two shafts 12 will transmit the motion from the left to the right hand side of the machine, although it may be preferred to provide a duplication of the gear 2, and pinion 7 on the right hand side of the machine.

The two crank link cylinder combinations at the right and left hand side of the machine are set at different angles in order to avoid a dead center and insure smooth operation.

The shafts 13 and 14 at the forward or delivery end of the machine serve merely as hangers for the cranks 15 and 16. The punch bars being journaled on the cross-rods 17, 17 and 18, 18, will move through a circular path always remaining in a horizontal plane.

35 The punch mechanism.

The punch bars 19 which carry the punches also carry a stripping mechanism. The bar 20 is merely apertured to receive the punches.

40 The preferred construction of the bar 20 comprises a lengthwise body 20 re-enforced by a rib 33 at each side of which are apertures 34, the apertures being, in this particular instance, formed in pairs lengthwise of the bar. The bar is surfaced by a plate 35 of suitable metal which has accurately formed apertures 36, 36, aligned with the apertures 34 and carefully formed to receive the punches of the upper bar.

45 The upper bar is formed of a body 19 re-enforced by a rib 37. The under side of this body has secured to it the plate 38. The plate 38 carries the punches 39 which are arranged in pairs lengthwise of the structure. The plate 38 is also socketed at 40 to form housings for springs 41^a, these sockets and springs being preferably four or five in number throughout the length of the bar, although, of course, the exact number is 50 unessential.

The body 19 of the bar is perforated for the passage of pins 41, 41, which extend through the sockets 40, above noted, and have mounted on their ends the stripper plate 42 which extends the whole length of

the bar mechanism. The springs 41^a bear on the stripper plate and the plate is accurately apertured to ride over the punches 39, 39.

It is so constructed that when a sheet of material is placed between two bars and the mechanism set in motion, the two bars will be brought up against or adjacent each other at the upper and lower limits of their rotation respectively with the punches perforating the paper and entering the apertures in the lower bar throughout the entire length of the bars.

The stripper plate comes into contact with the paper and lower bar simultaneously with the punches, or slightly in advance thereof, if desired. The one continued motion of the mechanism separates the two bars and the punches ride out of the lower bar and the stripper will lift the paper from the pin. The exact contactual relation of the two bars is not essential, as the only necessary operation is that of the punches and holes; the stripper being carried on the bars or separated from them.

Having thus described my invention, what I claim as new and desire to secure by Letters Patent is:—

1. In a rotary punch, the combination with operating mechanism, of a single pair of punch bar elements extending lengthwise of a web of paper to be punched, the one bar carrying an extended number of longitudinally arranged punches, and the other bar provided with a similar number of longitudinally arranged matching holes for the punches, and means actuated by the operating mechanism for moving said bars toward and away from each other through a rotary path while maintaining them in parallel with relation to each other and means for controlling the amount of material fed between said bars, whereby the holes shall be punched in spaced series for the several punching operations.

2. In a rotary punch, the combination with operating mechanism, of a single pair of punch bar elements extending lengthwise of a web of paper to be punched, the one bar carrying an extended number of longitudinally arranged punches, and the other bar provided with a similar number of longitudinally arranged matching holes for the punches, and means actuated by the operating mechanism for moving said bars toward and away from each other through a rotary path while maintaining them in parallel with relation to each other, and means for controlling the amount of material fed between said bars, whereby the holes shall be punched in spaced series for the several punching operations, said means also actuated by said operating mechanism.

3. In a rotary punch, the combination with an operating mechanism, of two pairs of upper and lower cross bars extending

- transversely of the web of paper to be punched, means connected with the operating mechanism for moving said cross bars toward and away from each other in a rotary path, and punch bar elements extending lengthwise of the paper web, one punch bar carrying an extended number of longitudinally arranged punches and the other punch bar provided with a similar number of longitudinally arranged matching holes for the punches, said punch bar elements journaled on the two upper and lower bars, and means for controlling the amount of material fed between said bars.
4. In a rotary punch, the combination with an operating mechanism of cross elements extending transversely with relation to the web to be punched and, adapted to move in a circular path toward and away from each other, punching elements carried on said shafts and extending longitudinally of the said web, each punching element carrying an extended number of punches and corresponding matching holes, means for adjustably positioning said elements in the desired number across said cross elements, and means for feeding and controlling the amount of material fed between said punching elements, said means adapted to carry the paper in a path longitudinally of the bar.
5. In a rotary punch, the combination with an operating mechanism of cross elements extending transversely with relation to the web to be punched and, adapted to move in a circular path toward and away from each other, punching elements carried on said cross elements and extending longitudinally of the said web, each punching element carrying an extended number of punches and corresponding matching holes, means for adjustably positioning said elements in the desired number across said cross elements, and means for limiting the feed of material between said punching element, said means being controlled by said operating mechanism.
6. In a rotary punch, the combination with an operating mechanism of two pairs of upper and lower cross bars adapted to move toward and away from each other in a circular path, the same mounted to extend transversely of the web to be punched, punch bar elements journaled on the two upper and two lower cross bars, said punch bar elements extending lengthwise of the web of paper to be punched, said elements carrying an extended number of longitudinally arranged punches and corresponding matching holes, and means connected to the operating mechanism for actuating one of said bars of one pair, and connection from the actuated bar to the other bar of said pair.
7. In a rotary punch, the combination with an operating mechanism of two pairs of upper and lower cross bars adapted to move toward and away from each other in a circular path, punch bar elements journaled on the two upper and two lower cross bars and extending longitudinally of the webs to be punched, said punch bar elements carrying an extended number of longitudinally arranged punches and correspondingly arranged matching holes, and means connected to the operating mechanism for actuating one of said cross bars of one pair, and connection from the actuated cross bar to the other bar of said pair, comprising cranks on the two bars, a reciprocating element and pivotal connection from said cranks to the reciprocating element.
8. In a rotary punch, the combination with an operating mechanism of two pairs of upper and lower cross bars adapted to move toward and away from each other in a circular path, punch bar elements journaled on the two upper and two lower cross bars and extending longitudinally of the webs to be punched, said punch bar elements carrying an extended number of longitudinally arranged punches and correspondingly arranged matching holes, and means connected to the operating mechanism for actuating one of said cross bars of one pair, and connection from the actuated cross bar to the other bar of said pair, comprising cranks on the two bars, a reciprocating element and pivotal connection from said cranks to the reciprocating element, said cranks, reciprocating element and pivotal connections being duplicated at each end of said actuated bar, and the other bar of its pair.
9. In a rotary punch, the combination with an operating mechanism of two pairs of upper and lower cross bars adapted to move toward and away from each other in a circular path, punch bar elements journaled on the two upper and two lower cross bars and extending longitudinally of the webs to be punched, said punch bar elements carrying an extended number of longitudinally arranged punches and correspondingly arranged matching holes, and means connected to the operating mechanism for actuating one of said cross bars of one pair, and connection from the actuated cross bar to the other bar of said pair, comprising cranks on the two bars, a reciprocating element, and pivotal connection from said cranks to the reciprocating element, said cranks, reciprocating element and pivotal connections being duplicated at each end of said actuated bar, and the other bar of its pair, and the cranks for the two ends of said actuated bar being set in different planes, to counteract a dead center.

JOHN Q. SHERMAN.
